UNITED STATES PATENT OFFICE.

EVALD HEBEL, OF COPENHAGEN, DENMARK.

DEVICE FOR SIGNALING CHANGES OF DRIVING IN AUTOMOBILES.

Application filed April 15, 1922. Serial No. 553,278.

To all whom it may concern:

Be it known that I, EVALD HEBEL, residing at Copenhagen, Denmark, have invented certain new and useful Improvements in Devices for Signaling Changes of Driving in Automobiles, of which the following is a specification.

This invention relates to a device for signaling changes of driving in automobiles.

- 10 When an automobile during driving is to turn or stop, the driver usually indicates this by a signal by hand. While such signals may be given and observed with reasonable ease, when given from an entirely open carriage—at any rate during day-time—this mode of signaling, which the driver in certain countries is obliged to perform, is extremely inconvenient when the driver sits inside of a closed or merely covered carriage, and at night any signaling of the kind here referred to will be almost impossible to observe. It has therefore been proposed to provide wings, maybe in connection with other signaling devices at conspicuous points of the carriage and to operate these devices from the driver's seat.

The present invention relates to a device adapted to operate such signals in extremely easy manner, the said device being entirely reliable and easy to re-adjust. The signals will be easy to observe from ahead as well as from behind, and in day-time as well as at night.

The invention is shown on the drawing, Fig. 1. showing, in front elevation, the operating box with the operating handle,

Fig. 2. the same in section along the line A—A of Fig. 3,

Fig. 3. the same in section along the line B—B of Fig. 2,

Fig. 4, shows one of the signal arms, partly in section.

Fig. 5. is a detail.

The device consists of a case 1 containing the power transmitting members, and two or maybe several wings serving as signals, and Bowden cables connecting the case and the said wings.

The case 1, which is disposed in front of the driver on the dash-board or at other suitable place, contains a horizontal shaft 2 adapted to be turned in bearings 3 by means of a handle 4 with pointer 5. The shaft 2 is provided with a square disc 6 disposed between two springs 7 in such a manner that the shaft may occupy only

four positions. On the shaft there are provided, furthermore, a couple of eccentrics 8 and 9 co-operating with the arms 10 and 11, which are pivoted about pins 12, and are fitted at top with segments 13 for attachment of each of the cables 14 and 15 passing, through flexible tubes 16, 17, each to its wing disposed at some conspicuous point of the carriage.

The right-hand wing is shown on Fig. 4. An arm 18 with a lug 19 for attachment to the carriage is fitted at top with a head 20 slotted for the inner end of the wing 21, which is pivoted about a pin 22. The flexible tube 16 is extended up to the head 20, and the end of the cable 14 enclosed in the tube is screwed onto the top portion 23 of the curved end of the wing.

The wing will normally hang down vertically or nearly vertically in the position indicated by a dot and dashed line in Fig. 4. If the carriage is to be turned to the right, the driver turns the handle in such a manner that the pointer 5 points to the right on the front face of the case 1, on which a suitable inscription may be provided.

When the handle is turned, the eccentric 9 will be turned so far that it will swing the arm 10 to the left, Fig. 2, and the cable 14 will thereby be tightened causing the wing 21 to be swung up into the position shown in Fig. 4, and it ought to be noted that when the handle 4 occupies the position shown in Fig. 1, none of the two wings will be raised.

When the handle 5 is now turned back into the original position, gravity will cause the wing to swing down again, inasmuch as the pull in the cable ceases.

When the handle is turned to the opposite side, the other eccentric 8 will swing the other arm 11 sideways and, exactly as described above, swing the other wing up.

If the handle is turned 180° from the position shown on the drawing, the two eccentrics will have turned both of the arms 10 and 11 sideways, so that both wings will be raised, and when the handle is turned still more, both wings in succession will sink down, when the shaft 2 has performed a full revolution.

For use after darkness has set in, there may be used an electric light signaling device consisting of an electric lamp disposed in a lamp casing 24 on top of the wing. The lamp casing, in front as well as at rear, is

covered by coloured glasses, so that for instance the glasses in the right-hand lantern may be green, and in the left-hand lantern red.

5 By way of a knife-switch consisting of a pair of springs 25 and a knife 26 provided on the inner end of the wing, the lamp is connected in series with another lamp 24 in the case 1. This last mentioned lamp may be 10 placed behind a correspondingly coloured glass in the front face of the case 1.

The wiring diagram proper is not shown on the drawing for the reason that it forms no part of the present invention, but it will 15 easily be understood that when the handle 4, on Fig. 1, is turned for instance to the left and, consequently the right hand wing is raised, the knife 26 of the wing will come into contact with the springs 25 and, thereby 20 close the circuit in such a manner that not only the lamp provided above this wing will be lighted and show green light, but also the corresponding lamp in the case 1 will become lighted, and will indicate to the 25 driver that the signal is being shown.

The invention may of course be varied in several manners without the scope of the invention being passed.

Having now particularly described and 30 ascertained the nature of my said invention, and in what manner the same is to be performed, I declare that what I claim is:—

35 1. A signaling device of the character described for use on automobiles, comprising a case, a shaft mounted in the case, a handle on the shaft, swinging arms mounted in the case, Bowden cables connecting the said arms to signaling members, and eccentric discs mounted on the shaft and adapted to swing

the said arms to operate the said signal members. 40

2. A signaling device of the character described for use on automobiles, comprising a case, a shaft mounted in the case, a handle on the shaft, swinging arms mounted in the case, segments provided on the free ends of the said arms, Bowden cables connecting the said segments with signal members, and eccentric discs mounted on the shaft and adapted to swing the said arms to operate 45 50 the said signal members.

3. A signaling device of the character described for use on automobiles, comprising a case, a shaft mounted in the case, a handle on the shaft, a pair of swinging arms pivotally mounted one at each side of the shaft, a segment on the free end of each arm, a cable connecting each segment with a signal member, and an eccentric disc mounted on the shaft and engaging each of said arms to 55 60 swing the same and operate the signal.

4. A signaling device of the character described for use on automobiles, comprising a case, a shaft mounted in the case, a handle on the shaft, spring means engaging the 65 shaft to retain same in any adjusted position, swinging arms mounted in the case, Bowden cables connecting the said arms to signaling members, and eccentric discs mounted on the shaft and adapted to swing the said arms to 70 75 operate the said signal members.

In testimony whereof I affix my signature in presence of two witnesses.

EVALD HEBEL.
